United States Patent Office.

WILLIAM H. BETTS, OF BROOKLYN, NEW YORK.

Letters Patent No. 76,981, dated April 21, 1868.

IMPROVEMENT IN WINDOW-SASH LOCK.

The Schedule referred to in these Letters Patent and making part of the same.

TO ALL WHOM IT MAY CONCERN:

Be it known that I, WILLIAM H. BETTS, of Brooklyn, in the county of Kings, and State of New York, have invented, made, and applied to use a certain new and useful Improvement in Sash-Fastenings; and I do hereby declare the following to be a full, clear, and exact description of the said invention, reference being had to the annexed drawing, making part of this specification, wherein—

Figure 1 is a plan of said sash-fastener, as in place.

Figure 2 is a vertical section of the same, with the sashes fastened.

Figure 3 is a similar view, with the locking-piece drawn back to allow the sashes to be moved.

Figure 4 is an elevation of the sash-fastener, locked.

Figure 5 is a view of the locking-piece, endwise of its slide; and

Figure 6 is a plan of a portion of the slide upon which the locking-piece passes, when the window is locked.

Similar marks of reference denote the same parts.

This sash-fastener is made in the form of a divided dove-tail or under-cut slide, one part being secured to one of the meeting-rails of the sash, and the other to the other meeting-rail, and upon these a locking-piece is fitted to slide, so that when drawn upon one of the parts, the sash can be opened, but when the locking-piece is moved to embrace both parts of the slide, the sashes are held firmly, and as this locking-piece slides at right angles to the meeting-rails, a knife or thin instrument inserted between the said rails, cannot be used to press back the locking-piece; hence this fastening is very secure, and the construction is such that it is very strong, simple, durable, and cheap.

In the drawing, *a* and *a'* represent portions of the meeting-rails of any ordinary sash. *b* and *c* are the portions of the under-cut or dove-tail slide, attached upon line with each other to the respective meeting-rails, *a* and *a'* of the sashes, by suitable screws, *d* and *e*. The under-cut or dove-tail portion of the slide, *b* is sufficient to receive the sliding locking-piece *h*, as in fig. 3, when the sashes are unlocked, but the slide *c* is only sufficient for receiving half of the locking-piece *h*, as seen in figs. 1, 2, and 4, so that the two parts, *b* and *c*, cannot be separated, and thereby the window-sashes are securely locked together. Upon the slides *b* and *c* are the projecting portions or flanges *f* and *g*, to determine the amount of motion of the locking-piece *h*, and a pin, *i*, entering a groove in the under surface of *h*, prevents the said locking-piece *h* becoming separated from the slide *b*.

A friction-spring may also be applied to prevent the locking-piece being shaken out of position in moving the sashes.

What I claim, and desire to secure by Letters Patent, is—

The divided under-cut or dove-tail slide *b c*, in combination with the sliding locking-piece *h*, the parts being constructed and applied substantially as set forth to form a sash-fastener.

In witness whereof, I have hereunto set my signature, this twenty-fifth day of January, 1868.
